UNITED STATES PATENT OFFICE.

VICTOR E. TRAGER, OF BURRWOOD, LOUISIANA, ASSIGNOR OF ONE-FOURTH TO HENRY S. TRAGER, OF BAY ST. LOUIS, MISSISSIPPI.

DRYING-RACK.

1,826,808.

Specification of Letters Patent. Patented Dec. 30, 1919.

Application filed May 4, 1918. Serial No. 232,491.

To all whom it may concern:

Be it known that I, VICTOR E. TRAGER, a citizen of the United States, residing at Burrwood, in the parish of Palmettoines and 5 State of Louisiana, have invented certain new and useful Improvements in Drying-Racks, of which the following is a specification.

This invention relates to new and useful 10 improvements in drying racks, and the primary object of the invention is to provide a drying rack that is portable, that is provided with a plurality of arms adapted to be positioned around the central support of 15 the rack when inoperative, and to swing out horizontally and radially disposed with respect to the support when operative, and the support being connected with a collapsible stand so that this type of rack is 20 adapted to be folded into a very compact article when it is desired to transport the same, and when operative, presents a maximum number of drying racks.

Another object of the invention is to provide a device of this character which is easily 25 and simply constructed, inexpensive to manufacture, and one which will be very efficient in operation.

With these and numerous other objects in 30 view, my invention consists of the novel features of construction, combination and arrangement of parts which will be herein referred to and more particularly pointed out in the specification and claims.

35 In the accompanying drawings:

Figure 1 is a side elevation of the device partly in section with the arms extended.

Fig. 2 is a similar view of the upper portion of the rack showing the arms folded,

40 Fig. 3 is a top plan view of the top supporting plate,

Fig. 4 is a plan view of the means for holding the free ends of the arms when the same are inoperatively positioned, and

45 Fig. 5 is a detail transverse section through a portion of the main supporting plate, showing one of the arms swung to operative position.

In describing my invention, I shall refer 50 to the drawings in which similar reference characters designate corresponding parts throughout the several views.

The numeral 1 designates the frame supporting standard of this device, which is 55 vertically disposed, and which is tubular,

having an open lower end for a purpose to be hereinafter more fully described. Carried on the upper end of the vertical standard 1 is a top plate 2, formed with a central opening and provided with a plurality of 60 apertures 3 therein, which are spaced adjacent the periphery of the plate, formed in the plate intermediate the periphery of the plate and the apertures and sloping downwardly toward and into communication with 65 the apertures are grooves 4, said groove portions extending outwardly toward the periphery of the plate for a purpose to be hereinafter more fully described.

Positioned through the apertures 3 in the 70 plate 2 are a plurality of arms 5 which have their outer ends curved as shown at 6 and adapted to hook over the edges of the plate to support the arms when inoperative, as clearly shown in Fig. 2 of the drawings, 75 and said arms having knobs 7 formed on their free ends. The portions of the arms adjacent the inner ends are curved as shown at 8, so that when the arms are swung to inoperative position, and the knobs are disposed beneath the plate 2 as is clearly shown in Fig. 5 of the drawings, the curved portions 8 of the arms will be disposed in the grooves 4 so as to enable the arms to be positioned horizontally and held in said position as is clearly shown in Fig. 1 of the drawings.

Positioned within the tubular support standard 1 of the device is a shaft 9, that is formed of two sections pivotally connected 90 as shown at 10, the upper section having a projecting portion 11 on the end thereof that is externally threaded, and which is adapted to extend through the opening in the plate 2 to be positioned in a threaded recess 12 in 95 the top of the standard 1, in order to securely connect the shaft 9 within the tubular standard 1 and hold the plate 2 in position thereon. Said shaft 9 has secured to the lower portion thereof a holding rack 13 having a body portion 13' provided with superposed annular flanges 14 and 15 the upper flange having its edge notched as shown at 16 to receive the portions of the rod 5 therein adjacent the knobs 7 and the lower flange 105 having its peripheral edge bent upwardly to form a retaining wall 15'. The knobs will be positioned within the flanges 14 and 15 and the knobs within the wall 15' of the flange 15 of this holding rack, as clearly 110

shown in Fig. 2 of the drawings. The rack 18 is shrunk or otherwise secured on the lower portion of the shaft 9 so that when the device is assembled and operative as 5 clearly shown in Fig. 1 of the drawings, it will be disposed directly beneath the lower end of the standard 1.

Connected with the lower end of the shaft 9 is a collapsible supporting stand which 10 comprises a sleeve 17 adjustably mounted on the shaft 9 and being adapted to be held in various adjusted positions by a set screw 18, said sleeve having projecting portions whereby the upper ends of legs 19 are hing- 15 edly connected therewith. The legs 19 are adapted to be held in operative position, as clearly shown in Fig. 1 of the drawings, by braces 20 which have their inner ends connected to a vertical rod 21 detachably 20 connected with the lower end of the shaft 9.

This type of drying rack is very simply constructed, and the various parts thereof are collapsible, so that the rack may be taken apart and formed in a very compact 25 article adapted to be easily moved from place to place. The vertical tubular standard 1 has the supporting arms that form the drying rack proper connected therewith as has been fully described, and the arms 30 when inoperative hang down from the plate 2, being supported by the hooks 6. When it is desired to position the arms horizontally, they are moved through the apertures 3 in the plate 2, and their inner ends are engaged 35 with the plate as is clearly shown in Fig. 5 of the drawings. The knobs 7 will limit the movement of the arms through the apertures, and their curved portions fitting in the grooves 4 that communicate with the 40 apertures in the plate 2, to securely hold said arms horizontally and radially disposed around the standard 1.

The supporting means for the standard comprise the shaft 9 that is formed of two 45 hingedly connected sections to facilitate folding and packing, and the upper end of the shaft is detachably connected with the top of the standard, when positioned therein as is clearly shown in Fig. 1 of the draw- 50 ings. The collapsible stand that is secured to the lower end of the shaft 9 is adjustably

connected therewith, so that the rack may be adjusted vertically to the desired height. The shaft 9, stand, and supporting standard 1 are all detachable, so that the rack may 55 be knocked down and collapsed to a very small and compact article so that it may be easily transported from place to place.

From the foregoing description taken in connection with the accompanying drawings, it is thought that a clear and comprehensive understanding of the construction, operation, and advantages of my invention may be had, and while I have shown and described the device as embodying a specific 60 structure, I desire that it be understood that such changes may be made in said structure as do not depart from the spirit and scope 65 of the invention as claimed.

Having fully described my invention, 70 what I claim as new and desire to secure by Letters Patent, is:

1. A device of the character described comprising a tubular standard having an internally threaded socketed head, a plurality 75 of swinging arms connected concentrically of the head and adapted to be brought from vertical to fixed horizontal position, a shaft formed of pivotally connected sections received within the tubular member and detachably engaged in the threaded socket in the head of the latter, and a stand for said shaft.

2. A device of the character described comprising a tubular standard having an internally threaded socketed head, a plurality 80 of swinging arms connected concentrically of the head and adapted to be brought from vertical to fixed horizontal position, a shaft formed of pivotally connected sections received within the tubular member and detachably engaged in the threaded socket in the head of the latter, a stand for 85 said shaft, and a holding rack having spaced superposed plates, the upper plate being formed with a notched edge to receive the arms when in lowered position, the lower plate being peripherally flanged to lock the arms engaged in the notched edge.

In testimony whereof, I affix my signature 90 hereto.

VICTOR E. TRAGER.
